H. H. Snow,

Water Wheel Regulator:

No. 100,942.

Patented Mar. 15, 1870.

United States Patent Office.

HERVEY D. SNOW, OF BENNINGTON, VERMONT.

Letters Patent No. 100,942, dated March 15, 1870; antedated March 11, 1870.

WATER-WHEEL REGULATOR.

The Schedule referred to in these Letters Patent and making part of the same.

To all whom it may concern:

Be it known that I, HERVEY D. SNOW, of Bennington, in the county of Bennington, and State of Vermont, have invented and made a new and useful Improvement in Regulators for Water-Wheels; and I do hereby declare the following to be a full, clear, and exact description of the said invention, reference being had to the annexed drawing making part of this specification, wherein—

Figure 1 is a vertical section of the said regulator longitudinally of the shaft;

Figure 2 is an end elevation of said regulator; and

Figure 3 is a plan showing portions of the stops and gearing.

Similar marks of reference denote the same parts.

This invention is an improvement upon that for which Letters Patent were granted me July 14, 1868, and reissued June 29, 1869.

My present invention has reference especially to an arrangement of mechanism that gives to the stops a slower movement, without necessarily varying the speed of movement of the gate, so that more time may be given to the gate in moving, or the gate can be more fully opened or closed without varying its speed.

I also provide means for adjusting the parts to compensate any wear.

When the gate is to be closed to stop the wheel, the regulator may be made to effect the movement, thereby the closing is very gradual, and the "ram" action in the feeding-trunk is prevented.

In the drawing—

a is the shaft that extends to the device that is connected with the gate to be operated upon.

b, the standard supporting the same.

f is the ratchet-wheel; and

h is the disk, arms, or wheel, with a pin, *m*, that is acted upon by the lever to the governor, and provided with a pin, *k*, that passes into the curved slot in the stationary plate *l*.

Around the shaft and its sleeve *n* is the hub of the pawl-carrier *o*, that is continuously oscillated by the connecting-rod *p* and crank on the shaft *q*, that is revolved by a connection to the shafting.

These parts thus far described are substantially the same as in the aforesaid patent, except in the particulars hereinafter named.

The disk *h*, instead of having a flanged rim cut out, is made with the adjustable stop flanges 27 28, that are connected by screws through slots, so that these flanges can be adjusted to allow for any wear, either of the pawls *r* and *s*, or the end of the flanges 27 or 28, so that the pawls may commence promptly to act upon the ratchet-wheel *f*, when there is any change

of speed, or for determining the point at which the governor commences to act on the ratchet-wheel.

This disk *h* might, however, be made of one piece, with a notched edge, instead of having the flanges 27 and 28 separately.

Instead of the stops *g* *g'* being applied to the side of the wheel *f*, as in the aforesaid patent, they are attached to the wheel *w*, that sets loosely around *n*.

These stops can be attached at any desired position on this wheel *w*, and perform the same duty of lifting the pawls from contact with the wheel *f*, when the gate has been fully opened or closed to the minimum point; but I cause these stops *g* *g'* to be brought around less rapidly than before, and this I effect by a slow revolving motion being given to the same by means of the gear *x* on the shaft or sleeve *n*, taking the wheel *y*, that in turn acts by the pinion *z* on the teeth around the periphery of the wheel *w*.

If the wheel *w* were attached to the sleeve *n* it could have but less than one revolution before the stops *g* or *g'* would lift the pawl and stop the gate-shaft *a*; but, by placing the wheel *w* loosely on the sleeve *n*, and applying the gearing as aforesaid, the shaft *a* revolves any desired number of times, according to the relative size of the gearing *x* *y* *z*, while the wheel *w* is revolving once, thus giving more time and a consequent further movement to the gate before the stops *g* or *g'* act, without necessarily varying the speed of the gate, which should be as rapid as practical to work the parts.

The ratchet-wheel *f* should be as small as possible, to get the required strength and leverage, and the wheel *w* must be smaller than *f*, to bring the stops *g* and *g'* under the pawls *r* *s*; consequently, if the wheel *w* moves at the same speed as shaft *a*, the range of adjustment of the stops *g* *g'* and the movement of the gates are limited, while, by applying the gearing to slow the wheel *w*, without altering the speed of sleeve *n* and shaft *a*, the range of adjustment and movement is not limited by the size of the parts.

If the speed of wheel *w* and shaft *a* were as one to five, the gate would move five times as long as when the speed of *w* and *a* were the same, and the gate could move five times as far.

To facilitate the use of this regulator, the tube or sleeve *n* extends from one side to the other, so that the shaft *a* may be led off in either direction to the wheel, and two shafts may be employed, running off in opposite directions to two gates and wheels.

The usual arrangement for closing the gate by hand may be provided if desired, the same acting to revolve the shaft *a*. This method of closing the gate should be retained and be available, as it may become necessary to close it suddenly, on account of derangement

of machinery; but to prevent back action of the water it should be shut off gradually, and I make the regulator available for that purpose.

The lever v and arm v' may be employed to bring the regulator into action in closing the gate, when said lever v is moved by hand to turn the disk h , by taking against the pin k , instead of its being moved by the governor by change of speed. This enables the attendant to bring the regulator into action in closing the gate or gates by the revolution of the shaft q and pawls, so that the action of stopping is very gradual, the attendant is relieved from a tedious duty, and risk of injury to the trunk or feeder by the "ram action" in closing the gate suddenly is avoided. This lever v may be operated by a cord running to any convenient part of the building, or by any other suitable means.

What I claim, and desire to secure by Letter Patent, is—

1. The stops 27 and 28, attached adjustably to the disk or arms h , in combination with the ratchet-wheel f and pawls $r's$, as and for the purposes set forth.

2. The wheel w , actuated by the gearing $x y z$, in combination with the stops $g' g$ and pawls $r's$, substantially as and for the purposes set forth.

3. The lever v , in combination with the disk h and pawls $r's$ and wheel f , as and for the purposes set forth.

4. The sleeve n , connected to the wheel f and receiving shaft a , as and for the purposes specified.

In witness whereof I have hereunto set my signature this 9th day of August, A. D. 1869.

H. D. SNOW.
